(57) **CLAIM**

The ornamental design for a photo storage box set as shown and described.

DESCRIPTION

FIG. 1 is a perspective view of a first component of a photo storage box set showing my new design shown separately for ease of illustration and in an open configuration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is an enlarged view of portion 9 shown in FIG. 1; FIG. 10 is an enlarged view of portion 10 shown in FIG. 1; FIG. 11 is an enlarged view of portion 11 shown in FIG. 2; FIG. 12 is an enlarged view of portion 12 shown in FIG. 5; FIG. 13 is an enlarged view of portion 13 shown in FIG. 6; FIG. 14 is an enlarged view of portion 14 shown in FIG. 8; FIG. 15 is a perspective view of a second component of the photo storage box set shown separately for ease of illustration and in a closed configuration; FIG. 16 is another perspective view thereof; FIG. 17 is a front elevational view thereof; FIG. 18 is a rear elevational view thereof; FIG. 19 is a left side elevational view thereof; FIG. 20 is a right side elevational view thereof; FIG. 21 is a top plan view thereof; FIG. 22 is a bottom plan view thereof; FIG. 23 is an enlarged view of portion 23 shown in FIG. 15; FIG. 24 is an enlarged view of portion 24 shown in FIG. 16; FIG. 25 is an enlarged view of portion 25 shown in FIG. 21; FIG. 26 is an enlarged view of portion 26 shown in FIG. 22; FIG. 27 is a perspective view of the photo storage box set, shown in use with the second component received in the first component; FIG. 28 is a perspective view of the first component of the photo storage box set, shown separately for ease of illustration and in a closed configuration; and,

(Continued)

FIG. 29 is an enlarged view of portion 29 shown in FIG. 28. The dash-dash broken lines immediately adjacent to the shaded areas depict the bounds of the claimed design, while the other dash-dash broken lines in FIG. 27 are directed to environment, both form no part of the claimed design. The dot-dash broken lines represent boundaries of the enlarged portions and form no part of the claimed design.
